Patented Jan. 26, 1915.

UNITED STATES PATENT OFFICE.

HENRIK EMIL RIISAGER, OF FREDERIKSBERG, DENMARK, ASSIGNOR TO F. L. SMIDTH & CO., OF NEW YORK, N. Y., A CORPORATION OF NEW JERSEY.

PROCESS OF WET GRINDING.

1,126,085.

Specification of Letters Patent. Patented Jan. 26, 1915.

Application filed April 18, 1912. Serial No. 691,621.

To all whom it may concern:

Be it known that I, HENRIK EMIL RIISAGER, a subject of the King of Denmark, residing in Frederiksberg, Denmark, have 5 invented certain new and useful Improvements in Processes of Wet Grinding, of which the following is a specification, reference being had to the accompanying drawing, which forms a part hereof.

10 In the manufacture of cement by the so-called wet process, in which the cement materials are ground in the presence of water to form a thick, creamy mass, called slurry, and in which the slurry is delivered to a rotary kiln where the moisture is driven off and the raw material is burned, it is necessary that the slurry shall have a definite and uniform consistency in order that the process may be carried on economically and with 15 uniform results. In order that the slurry may have such definite and uniform consistency it is necessary that the quantity of water with which the material is ground in the grinding mill shall be regulated in accordance with the character of the material being ground and the results to be accomplished. The proper quantity of water should be kept in the grinding mill at all times. If the water escapes too freely the 20 material balls up in the machine, gradually closing the outlets and preventing proper operation. If too much water is kept in the grinding mill, the slurry is too thin or liquid and the efficiency of the plant is reduced. 25 The mill in which the grinding of the material is carried on and this invention practised is a drum or shell which is rotated upon a horizontal axis and to which the material to be ground and the water are delivered at 30 one end while the slurry is discharged at the other end.

The object of the invention is to improve the wet process referred to above and provide a method by which it can be carried on 45 and the proper quantity of water kept in the mill at all times, while provision is made whereby the quantity of water kept in the mill can be varied to suit different conditions.

50 In accordance with the invention the process is practised in a drum provided at the discharge end with a series of openings which are disposed between the center and the periphery in place of the central opening which usually surrounds the shaft of the

drum, the grates being readily removable so that others can be substituted to vary, according to special conditions, the quantity of water retained in the drum.

The invention will be more fully explained 60 hereinafter with reference to the accompanying drawing in which is illustrated the preferred embodiment of apparatus for practising the improved process and in which—

65 Figure 1 is a view in longitudinal section of a wet grinding drum to which the invention is applied, a portion of the feeding devices for material to be ground and for water being also indicated. Fig. 2 is a view in 70 section on the plane indicated by the line 2—2 of Fig. 1, looking in the direction of the arrows. Fig. 3 is a detail view in elevation of one of the frames to which the grates are riveted. Fig. 4 is a detail view of the 75 same in section. Figs. 5 and 6 are similar views of one of the grates. Figs. 7 and 8 are similar views of another grate which may be put in the place of that shown in Figs. 5 and 6. Fig. 9 is a detail view of a 80 closure which may be put in place of any of the grates. Fig. 10 is a fragmentary view in section showing a portion of the head of the drum and showing the application there- 85 to of a frame and grate constructed in accordance with the invention.

Except with respect to the openings through which the slurry is discharged, the mill may be of any usual or suitable construction. As shown it comprises a cylindrical drum *a*, provided with a suitable lining *b*, and mounted through its feed head *c* and discharge head *d* upon a shaft *e* which is mounted to rotate in suitable bearings not shown. The feed head *c* has a central feed 90 opening *f* through which the material to be ground is delivered through a feed chute indicated at *g*, the water being supplied to the feed chute through a pipe *h*. The discharge head *d* is provided, between the center and 100 the periphery, and preferably nearer the periphery than the center, with openings *i* which are preferably arranged symmetrically. To the head *d*, about each opening *i*, is riveted a frame *k*, provided in its edge 105 with under cut slots *k'* to receive the heads of bolts *l* by which the grate frame *m* is removably secured in place, the latter frame being also provided in its edge with slots *m'* for the bolts *l*. The grate *n* or *n'* or the 110

closure n^2 is preferably riveted to the frame m and, as shown, in the drawing each grate is provided with openings n^3 which flare outwardly so as to prevent the clogging of the openings by the slurry. The grate n is provided with openings over its whole available area and grates of this kind are intended to be used when the quantity of water to be kept in the drum is minimum. The grate $10 n'$ shown in Figs. 7 and 8, has openings n^3 only in that portion which lies nearest the axis of the drum and is intended to be used, in place of the grate n , when a larger quantity of water is to be retained in the drum. 15 A complete closure n^2 , shown in Fig. 9, may be substituted for one or more of the grates if it is desired to reduce still further the escape of water from the drum. It will be understood that each grate preferably has 20 its own frame and can be substituted quickly for any other grate. Obviously the grates might be formed integral with the frames m , but for convenience in manufacture they are formed separately therefrom and are 25 riveted thereto.

The operation of wet grinding is carried on with the improved mill substantially as in an ordinary mill, but it will be seen that by disposing the discharge openings between 30 the center of the drum and the periphery the slurry can escape only when it has accumu-

lated in the drum to a height above the lowest point of the frame equal to the distance of the nearest opening n^3 in the lowermost grate n from such point, whereby the desired quantity of water is retained in the frame. By making the grates interchangeable, as shown, it becomes possible to regulate the escape of the slurry and the quantity of water retained in the drum and it 35 is with the improved method of regulating the quantity of water and the consistency of the slurry that this invention is concerned. 40

I claim as my invention:—

The improvement in the manufacture of cement by the wet process, which consists in placing the cement materials with water in a rotary drum to form slurry, regulating the consistency of the slurry by varying the 50 effective radial distance of the openings in the discharge head of the drum through which the water and the slurry escape from the drum, and thereafter driving off the moisture from the slurry and burning the 55 residue.

This specification signed and witnessed this 2nd day of April A. D., 1912.
